FIGURE 1 is a perspective view of a first embodiment; FIGURE 2 is a top plan view of the first embodiment; FIGURE 3 is an end view as seen from below in FIGURE 2;

FIGURE 4 is an end view as seen from above in FIGURE 2;

FIGURE 5 is a side view as seen from the left-hand side of FIGURE 2;

FIGURE 6 is a perspective view of a second embodiment;

FIGURE 7 is a top plan view of the second embodiment;

FIGURE 8 is an end view as seen from below in FIGURE 7;

FIGURE 9 is an end view as seen from above in FIGURE 7;

FIGURE 10 is a side view as seen from the left-hand side of FIGURE 7;

FIGURE 11 is a perspective view of a third embodiment;

FIGURE 12 is a top plan view of the third embodiment;

FIGURE 13 is an end view as seen from below in FIGURE 12;

FIGURE 14 is an end view as seen from above in FIGURE 12;

FIGURE 15 is a side view as seen from the left-hand side of FIGURE 12;

FIGURE 16 is a perspective view of a fourth embodiment;

FIGURE 17 is a top plan view of the fourth embodiment;

FIGURE 18 is an end view as seen from below in FIGURE 17;

FIGURE 19 is an end view as seen from above in FIGURE 17;

FIGURE 20 is a side view as seen from the left-hand side of FIGURE 17;

FIGURE 21 is a perspective view of a fifth embodiment;

FIGURE 22 is a top plan view of the fifth embodiment;

FIGURE 23 is an end view as seen from below in FIGURE 22;

FIGURE 24 is an end view as seen from above in FIGURE 22;

FIGURE 25 is a side view as seen from the left-hand side of FIGURE 22;

FIGURE 26 is a perspective view of a sixth embodiment;

FIGURE 27 is a front view of the sixth embodiment; FIGURE 28 is an underside view as seen from below in FIGURE 27;

FIGURE 29 is a top view as seen from above in FIGURE 27;

FIGURE 30 is a side view as seen from the left-hand side of FIGURE 27;

FIGURE 31 is a perspective view of a seventh embodiment;

FIGURE 32 is a top plan view of the seventh embodiment;

FIGURE 33 is an end view as seen from below in FIGURE 32;

FIGURE 34 is an end view as seen from above in FIGURE 32;

FIGURE 35 is a side view as seen from the left-hand side of FIGURE 32;

FIGURE 36 is a perspective view of an eighth embodiment;

FIGURE 37 is a front view of the eighth embodiment;

FIGURE 38 is an underside view as seen from below in FIGURE 37;

FIGURE 39 is a top view as seen from above in FIGURE 37; and

FIGURE 40 is a side view as seen from the left-hand side of FIGURE 37.

The dominant features of my design reside in the portions shown in full lines.

I claim:

The ornamental design for a telephone instrument, as shown and described.
